UNITED STATES PATENT OFFICE.

FREDERIC SCHAEFER, OF BOSTON, MASSACHUSETTS, ASSIGNOR, BY DIRECT AND MESNE ASSIGNMENTS, TO LEOPOLD SCHLEGELMILCH, TRUSTEE, OF SAME PLACE.

ELECTRIC SWITCH.

SPECIFICATION forming part of Letters Patent No. 322,857, dated July 21, 1885.

Application filed November 26, 1884. (No model.)

To all whom it may concern:

Be it known that I, FREDERIC SCHAEFER, of Boston, county of Suffolk, State of Massachusetts, have invented an Improvement in 5 Electric Switches, of which the following description, in connection with the accompanying drawings, is a specification, like letters on the drawings representing like parts.

My invention relates to an electric switch 10 for opening and closing an electric circuit, it being specially adapted for use in connection with a fixture or bracket for incandescent lamps. The operative parts of the switch are inclosed in a shell or case provided with screw-threaded fittings for connecting it with the bracket or tubing through which the conducting-wires pass, the said switch being provided with plates supported on a block of insulating material, and provided with contact-pieces 15 having yielding uprights, the said plates being adapted to be connected with the portions of a wire passing through the tube in either direction from the switch. The circuit is completed between the said yielding uprights or 20 is opened, as may be desired, by means of a movable connecting-piece fastened to a pivoted spindle or key provided with a handle to be turned by the operator, the said connecting-piece being substantially at right angles to the 25 said spindle and adapted to be placed in an intermediate position between the said yielding uprights, leaving them entirely disconnected, or to be placed in contact with both of them, completing the circuit between them. Suitable 30 shoulders or stops are provided to limit the movement of the movable connecting-piece, one of the said stops consisting of a shoulder on one of the stationary yielding uprights and the other consisting of a shoulder at the 35 40 end of a curved arm at one end of the movable connecting-piece.

Figure 1 is a side elevation of a switch embodying this invention; Fig. 2, a plan view of the operative portions of the switch, the 45 cap or cover of the inclosing-case being removed, and Fig. 3 a longitudinal section thereof on line *xx*.

The circuit-controlling portions of the switch are inclosed in a metallic case or shell, 50 *a*, provided with a removable cap or cover, *b*,

and with screw-threaded projections *c c'*, by which it may be connected with the tubing of a fixture or bracket or other tubing containing the electrical conductors forming the circuit, one of the said conductors being severed 55 where it passes through the switch, and the portions *d d'* thereof, leading from the said switch in opposite directions, being connected with metal plates *e e'*, as shown in Fig. 2, secured upon a block, *f*, of insulating material, 60 fastened within the case or shell *a* by the screws *g*. The said plates *e* are provided with stationary but somewhat yielding upright pieces *h h'*, which thus form the terminals of the circuit, which may be completed between 65 the said yielding uprights *h h'* when desired by a movable connecting-piece, *i*, attached to a spindle, *k*, having a rotary movement in a socket in the insulating-block *f* midway between the said yielding uprights *h h'*, the end 70 of the said spindle being slotted, as shown at Fig. 3, to receive the connecting-piece *i*, which is securely fastened to the said spindle by a nut, *m*, screwed onto the end of the said spindle and engaging the said movable connecting-piece *i*, which is preferably made of copper, on account of its high conductivity. The spindle *k* is provided with a suitable handle, *k'*, to enable it to be turned, and when in the position shown in Figs. 2 and 3 the connecting-piece *i* extends directly across between the yielding uprights *h h'*, making electrical connection between them, and by a quarter-rotation of the said spindle the connecting-piece 75 *i* will be removed from the yielding upright *h*, thus breaking the circuit between *h* and *h'*. The movement of the connecting-piece *i* by the key or handle *k'* in either direction to open or close the circuit, as may be desired, is limited by suitable stops, one of which consists of a 80 shoulder, *h''*, or flange at the edge of the yielding upright *h*, which by its engagement with the end of the connecting-piece *i* prevents further rotation thereof when moved to close the circuit. The other end of the connecting-piece *i* is provided with a curved arm, *i'*, having at its end a shoulder or projection, *i''*, which, when the said connecting-piece is 85 turned a quarter-rotation from the position shown in Fig. 1, in order to break the circuit, 90 95 100

engages the edge of the yielding upright h' , preventing further rotation of the connecting-piece. The pressure of the yielding uprights h h' against the ends of the connecting-piece i 5 produces considerable friction, tending to resist the movement thereof when the key is turned by the operator, and when the operator in turning the key to break the circuit moves the end of the connecting-piece i from the 10 yielding upright h^2 the sudden reduction in pressure will cause the said connecting-piece to move quickly away from the stationary yielding upright, thus breaking the circuit suddenly and completely, as is desired. The 15 cover b affords access to the operative portions of the switch, so that they may be readily adjusted or covered.

I claim—

1. An inclosing-case, an insulating-block 20 therein, and contact-pieces supported on the said block, each provided with a yielding upright, combined with the actuating-spindle pivoted between the contact-pieces and provided with a connecting-piece one arm of 25 which engages one of the yielding uprights, and the other arm provided with a curved portion forces the second yielding upright from its normal position when the spindle is turned to break the circuit, the said yielding 30 upright holding the connecting-piece in a given position in open circuit until the said spindle is positively moved to close the circuit, substantially as described.

2. The inclosing-case and insulated block secured therein, the said block having contact-pieces rigidly attached thereto and provided with yielding uprights, one of the said uprights having a shoulder, combined with the actuating-spindle provided with a connecting-piece having one arm engaging the shouldered 40 upright to close the circuit, and a second arm provided with a curved finger having a projection, the said curved finger engaging the second yielding upright when the circuit is closed, and forcing the said yielding upright 45 from its normal position, being held in engagement therewith by the action of the said yielding upright when the circuit is opened, substantially as and for the purpose specified.

3. An inclosing-case provided with contact-pieces, combined with an actuating-spindle having a key at its loose end and being provided with screw-threads and a transverse slot, 2, and the retaining-nut, and a connecting-piece to engage the yielding uprights of 50 the contact-pieces, the said connecting-piece resting in the slotted end of the spindle, substantially as described.

In testimony whereof I have signed my name to this specification in the presence of two 55 subscribing witnesses.

FREDERIC SCHAEFER.
